UNITED STATES PATENT OFFICE

SAMUEL SHEINDELMAN, OF LAWRENCE, NEW YORK

SWEATER

Application filed January 3, 1933. Serial No. 649,873.

This invention relates to garments and more specifically to an article of apparel suitable for feminine wear.

A major object of the invention is in the provision of a garment having a body portion of a single piece of knitted goods.

Another object is in the provision of a garment in which the body and sleeve portions are integrally made and to which are suitably secured cuff and waistband portions and a collar of pleasing design.

A still further object is to provide an article of apparel in which the integral body and sleeve portions are arranged with stripes of pleasing pattern and color, and though the stripes are arranged vertically in the whole garment when stretched in flat condition, these stripes when the garment is worn appear vertically disposed on the body portion and horizontal on the sleeve portions.

Another important object of the invention resides in a new method of constructing a garment which consists in providing a substantially rectangular blank of knitted material doubling it over on its central longitudinal dimension, suitably stitching along the open bottom from each lower outside corner toward the vertical middle of the body portion to provide sleeve portions, affixing cuff portions and a waistband portion, cutting out a proper neck portion and attaching a suitable collar thereto.

A further object resides in providing a blank of knitted material having contrasting colored stripes, said material being knitted on a conventional type of flat or circular knitting machine having a conventional striping attachment which produces only horizontal stripes on the material. A blank so produced would have its wales transverse to the stripes and when formed into a garment, the striping would be vertical and the wales run horizontally across the body.

A still further object is in the provision of a garment having a one piece body and sleeve portion, seamless shoulders and stripes vertically disposed in the body portion and horizontal in the sleeve portions with the wales of the material across the body.

These and many other objects and advan-

tages will be more clearly seen from the following specification, description of the accompanying drawing which illustrates a preferred embodiment of the invention and the manner of constructing same, and in which:

Fig. 1 illustrates in perspective a garment constructed in accordance with the invention.

Figs. 2 to 6, inclusive, indicate the various steps in a preferred method for producing the garment illustrated in Fig. 1.

Fig. 7 indicates the manner in which the material blank is knitted.

In greater detail, the garment 10 comprises a front and back body portion 11 having integral sleeve portions 12. The lower portion of the body portion is preferably provided with a stretchable waist band 13, and the sleeve portions similarly provided with stretchable cuffs 14. An opening 15 for the neck of the wearer is indicated and may be arranged with a collar 16 of pleasing conformity.

The top portion of the garment along the sleeves and shoulders is seamless as indicated at 17 and the material from which the body and sleeve portion is integrally made may be arranged with stripes of pleasing design and color as shown at 18.

The garment above described may be constructed in the following manner:

A piece of material is knitted of a suitable width such as indicated by the dimension line "W" and of a length "L" commensurate to the needs of the finished garment. This piece of material is stretchable in all directions but has its wales running along the dimension "W".

One preferred method of producing the blank of material is best illustrated in Fig. 7 where the material is shown as produced by a conventional form of flat or circular knitting machine. When so produced its length is greater than its width and the stripes are horizontally disposed. When severed along the line "A" and employed as hereinafter described, a garment having vertical stripes and horizontal wales is produced.

The material may then be folded along a line 19. The result of this folding is shown in Fig. 3, and then trimmed away as at 20,

(Fig. 4), to shape the piece of material for the garment.

The material is then stitched as shown at 21 and the neck portion cut out as shown at 5 15 and is then ready for application for the sleeve cuffs, waistband and collar as most clearly shown in Figs. 1 and 6.

It is also conceivable to form the neck opening during the knitting of the piece as 10 represented by the numeral 15a (Fig. 2).

It is now apparent, that a garment of esthetic appearance and beautifully striped and colored may be simple and inexpensively made. The pleasing effect of the seamless 15 shoulders and flaring sleeves is greatly desired by the discriminating wearer and of greatest importance is the increased wearing 20 qualities of the garment due to the seamless shoulders and lack of seam where the sleeves meet the body, it being proven time and again that garments of this class which have inset sleeves are weakest at that point.

While the above specification is quite detailed in describing a preferred garment 25 structure and method for making the same, no undue limitations in the breadth of the invention as defined by the appended claims, are intended.

What is claimed as new and desired to be 30 obtained by Letters Patent is:

1. In a knitted garment to be worn by females, a body portion having a longitudinal over-all width measuring from cuff to cuff of the arms of the female when the same are 35 in a horizontal outstretched position, and having a vertical length substantially uniform throughout the width of the garment, the wales of the body portion running in the same horizontal direction, said garment having front and back portions and a defined 40 neck opening, the body portion being of such width as to extend from the shoulders to below the bust of the wearer, the front and back portions of the garment being joined 45 together at the bottom defining sleeve portions of a width substantially equal to the width of the garment.

2. A new article of manufacture, a garment 50 of the class described comprising a substantially rectangular piece of knitted material provided with a neck opening and having its wales running in the direction of its longer dimension, the material being doubled over along its medial longitudinal line and 55 stitched together at the bottom from each outside lower corner towards the vertical middle of the material, thereby forming sleeve portions and a body portion, said garment being of such width as to extend from the shoulders to below the bust portion of the wearer.

3. A new article of manufacture, a garment 60 of the class described comprising a substantially rectangular piece of knitted material provided with a neck opening and hav-

ing its wales running in the direction of its longer dimension, and having colored stripes coextensive with its shorter dimension, the material being doubled over along its medial longitudinal line and stitched together at the bottom from each outside lower corner towards the vertical middle of the material, thereby forming sleeve portions and a body portion, said garment being of such width as to extend from the shoulders to below the bust portion of the wearer, and a waist band attached to said body portion.

Signed at New York, in the county and State of New York.
